INVENTOR

John R. Dooty

UNITED STATES PATENT OFFICE

JOHN R. DOOTY, OF LIBERAL, KANSAS, ASSIGNOR TO CLARENCE P. WILLIAMS, OF MIAMI, OKLAHOMA

LATCH LUBRICATOR

Application filed July 6, 1931. Serial No. 548,986.

My invention relates to lubricators for latch-bolts on swinging closures, and is more particularly designed for use upon automobile doors.

The objects of my invention are to provide a device of this class which is new, novel, practical and of utility; which may be easily and quickly installed adjacent and beneath the usual keeper of a door latch by merely loosening the usual screws or bolts which hold the keeper in place; which is constructed of a single sheet of bendable metal and a single fibrous pad, the pad being retained in position on the sheet by an integral convolute portion or portions thereof, thus permitting the entire sheet to be formed and the pad installed by a single operation of a stamping machine; which has no moving parts to become worn or to get out of order; which will thoroughly lubricate the bevelled end of a latch-bolt; which will act as a silencer to prevent squeaks and rattles, as well as acting as a shock absorber for the latch-bolt when a door is closed; which will be durable; which is comparatively cheap to manufacture; and, which will be efficient in accomplishing all of the purposes for which it is intended.

There have been in the past some devices perfected for lubricating the bevelled free end of a latch-bolt, but so far as this applicant knows or has been able to ascertain these devices are all constructed so that they move with the latch-bolt as its free end enters the latch-plate or keeper. This necessarily causes them to wear more severely than would a stationary pad. They are also more complicated to manufacture and install than is applicant's device.

Applicant is also familiar with a number of devices designed to silence the contact of a latch-bolt with its keeper, but so far as he knows or has been able to ascertain these devices are all considerably more complicated to install and manufacture and are much more expensive than his device.

With these and other objects in view as will more fully appear, my invention consists in the construction, novel features, and combination of parts hereinafter more fully described, pointed out in the claims hereto

appended, and illustrated in the accompanying one-sheet drawing, of which,

Figure 1 is a fragmentary view of a door jamb showing a usual type of latch-plate or keeper in place, and showing the device installed for use;

Fig. 2 is a perspective view of the device; and,

Fig. 3 is a view similar to that of Fig. 2, showing the bevelled end of a usual latch-bolt seated upon the lubricating portion of the device.

Like characters of reference designate like parts in all of the figures.

It is understood that various changes in the form, proportion, size, shape, weight, and other details of construction, within the scope of my invention may be resorted to without departing from the spirit or broad principle of my invention and without sacrificing any of the advantages thereof; and it is also to be understood that the drawing is to be interpreted as being illustrative and not restrictive.

One practical embodiment of the invention as illustrated in the drawing follows:

The device as a whole is indicated by the reference numeral 1, and consists substantially of a sheet of metal which at one end is bifurcated to form parallel flat legs 2. The other end portion of the device is arcuately formed to seat within the usual cavity in a jamb member 9 for seating the free bevelled end of a usual latch-bolt 3. This arcuate portion is indicated by the reference numeral 10 and its inner surface is covered by a fibrous pad 11 held in place by a convolute portion 12 of the sheet forming the device. Said pad 11 is adapted to be saturated with a desired lubricant.

In Fig. 1, the reference numeral 4 indicates a usual keeper which is held in position upon the jamb member 9 by a plurality of bolts or screws 5 and 6. Said keeper 4 is so positioned that one end coincides with one side of the previously mentioned cavity within which the arcuate portion 10 of the device is positioned.

In installing the device upon the jamb member 9, all that is necessary is to loosen the

screws 5 and 6 a short distance; insert the legs 2 between the keeper 4 and the face of the jamb member 9, the legs assuming a position upon each side of the screws 5 and 6; 5 and, to then re-tighten the screws.

It may be seen from the foregoing description that applicant has provided an extremely simple device which will accomplish all of the purposes for which it is intended.

10 Obviously, the invention is susceptible of embodiment in forms other than that which is illustrated in the accompanying drawing and described herein, and applicable for uses and purposes other than as detailed, and I 15 therefore consider as my own all such modifications and adaptations and other uses of the form of the device herein described as fairly fall within the scope of my invention.

Having thus described my invention, what 20 is claimed and desired to be secured by Letters Patent is:

25 1. An oiling device for the free end of a latch-bolt, consisting of a single plate of thin metal having a pad of fibrous material for receiving oil, said pad caught in a convolute portion of said plate adjacent one end thereof, said plate having two integral legs for insertion between a keeper and its supporting member for rigidly positioning the pad at 30 one end of the keeper for seating the free end of a latch-bolt.

35 2. An oiling device for the free end of a latch-bolt, consisting of a single plate of thin metal having a pad of fibrous material for receiving a lubricant, said pad caught in a convolute portion of said plate adjacent one end thereof, said plate having two parallel integral legs for insertion between a keeper and its supporting member so as to straddle the 40 usual keeper positioning screws for rigidly positioning the pad at one end of the keeper for seating the free end of the latch-bolt when the keeper positioning screws are tightened.

45 3. In testimony whereof I affix my signature.
JOHN R. DOOTY.
